UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed April 16, 1923. Serial No. 632,419.

This invention relates to window control mechanisms and particularly relates to mechanisms for actuating the sliding windows of motor vehicles.

The invention consists in the structural features hereinafter set forth.

In the drawings:—

Figure 1 is an interior view of an automobile door having a window equipped with 10 the improved control means;

Figure 1^a is a section on line 1^a—1^a of Figure 1;

Figure 2 is an enlarged view of the control mechanism;

15 Figure 3 is a reverse view of the same;

Figure 4 is a cross sectional view of said mechanism taken on line 4—4 of Figure 2.

In these views, the reference character 1 designates an automobile door having in its 20 upper portion the window opening 2 and provided with a closure for said opening having the nature of a vertically slidable glass plate 3. Said closure, when lowered, is adapted to enter a chamber 4 formed in

25 the lower portion of said door. 5 designates the usual lock board rigidly connecting the side uprights of the door just below the window opening. The present invention locates a control mechanism within the chamber 4,

30 mounting said mechanism upon a vertically elongated sheet metal plate 6, the extremities of which are respectively secured to said lock board and to the bottom sill of the door. At substantially a mid-point 7 of

35 said plate 6 there is pivoted upon said plate a lifter arm 8 which terminally carries a roller 9 engaging in a channel strip 10 depending from the closure 3. The pivotal end portion of said arm 8 is extended slightly

40 beyond the pivot element 7 for terminal engagement by a coiled spring 11 downwardly extended to engage an anchorage hook 12 secured within a slot 13 in the lower end portion of said plate 6. The upper end portion

45 of said plate is correspondingly positioned with a slot 13' to function similarly to the slot 13 in case the mounting plate is turned end for end as will hereinafter be explained.

50 The pivotal element 7 is in the nature of a stub shaft journaled in a bearing 12' rigidly engaged with the plate 6, said shaft rigidly carrying the control handle 13^a adjacent

the interior surface of the door. A lost motion actuating connection between said handle and the arm 8 is provided, the lost motion movement being utilized to release latch means whereby the arm 8 is adapted to be held positively adjusted. Thus, there is rigidly mounted upon the shaft 7 a cam plate 14 of triangular shape, said shaft engaging one apex of said plate. At its other apices said plate is formed with lugs 15 projecting transversely to said plate in the plane of travel of the arm 8, the latter being loosely mounted upon the shaft 7 and retained in place thereon by said cam plate. A wire spring 15^a engages the shaft 7 and the plate 14 to normally maintain a neutral position of said plate with respect to the control arm, that is to say, said lugs being normally held by said spring equi-distantly spaced from said arm. 16 is a cam slot in the plate 14 having portions angularly intersecting at the center line of the plate. Into said slot there projects a pin 17 carried by a latch bolt 18 slidable longitudinally upon the arm 8 and outwardly urged upon said arm by a coil spring 19 into normal engagement with a semi-annular toothed rack 20, the control arm during its angular travel being held in proper proximity to said rack by a guide bracket 21 fast upon said arm.

In the use of the described control mechanism, turning of the control handle 13^a in either direction initially rocks the cam plate 14 without affecting the arm 8. Through rocking of said plate, the cam edge of the plate 14 acts upon the pin 17 to retract the latch bolt 18 and release the latter from the arcuate rack 20. Continued turning of the handle 13^a acts through engagement of one or other of the lugs 15 with the arm 8 to swing said arm up or down according to the direction of turning of the handle, the latch bolt being retained in retracted position by the plate 14 during such lifting or lowering movement.

It is to be observed that the entire described mechanism, including the coiled spring 11, has a unitary mounting upon the plate 6, installation of the device being thus facilitated. Also, said mounting permits the location of the mechanism as regards the relative spacing from the two uprights of the door to be selected at will, since obvious-

ly the mounting plate 6 may be moved to or from either upright without affecting the operation.

Another desirable feature lies in the fact that the same control unit is applicable for use either in a right hand or left hand door of a vehicle. That is to say, the mounting of the mechanism upon the plate 6 centrally with respect to the ends thereof permits the mounting plate to be turned end for end to adapt the unit for use on either of the opposite side doors of a vehicle. The two slots 13 and 13' permit the spring 11 to be downwardly extended and engaged with either end of the plate 6 which may be secured to the sill of the door.

The arcuate rack 20 is of sufficient diameter to permit accurate engagement thereof by the teeth of the latch bolt 18 without appreciable backlash. Because of the arcuate form of the rack 20, the variation in the vertical position of the closure resulting from shifting the latch member a distance of one notch with relation to said rack when the closure is substantially raised is quite slight and this is conductive to accuracy and establishing a definite closed position.

What I claim as my invention is:—

1. A window control mechanism comprising a pivotal arm for engagement with a sliding closure, actuating means for said arm, and a mounting plate mounted upon a transverse frame member and carrying said arm and actuating means substantially at a mid-point of said plate, whereby said plate carrying said arm and actuating means is reversible to adapt the mechanism for use upon right hand or left hand windows of a vehicle.

2. In a window control mechanism, the combination with a sliding closure and a chamber receiving the same in open position, of a control mechanism disposed within said chamber comprising a mounting plate mounted upon a transverse frame member and elongated in the direction of travel of the closure, and a control arm and actuating means therefor mounted upon said plate substantially midway of its length, whereby said plate carrying said mechanism is reversible end for end to adapt said mechanism for right hand or left hand use in a vehicle.

3. A window control mechanism comprising an elongated mounting plate, a control arm pivotal upon said plate substantially midway of its length, actuating means for

said arm carried by the plate, and a counterbalance spring extending from said arm alternatively to either end portion of said plate.

4. A window control mechanism comprising a mounting plate, a control arm pivoted thereupon, an arcuate rack mounted upon said plate and having its center of curvature at the pivot of said arm, a latch member slidable upon the arm for engagement with said rack, an actuating member engaging the pivot of said arm, and a lost motion connection between said actuating member and arm, retraction of said latch member being effected by the lost motion movement.

5. In a window control mechanism a pivotal control arm, a copivotal cam plate having lugs engaging at opposite sides of said control arm, a spring acting on said cam plate maintaining said plate normally equidistant from said arm, a latch member slidably longitudinally upon said arm and retractable by said cam plate through rocking thereof, a stationary coacting latch element, and an actuating member connected to said cam plate.

6. In a window control mechanism, a pivotal control arm, a copivotal cam plate movable relative to said arm and having portions alternatively engageable with said arm for moving the same in opposite directions, a stationary latch element, a cooperating latch element upon said arm and movable relative thereto, means upon said cooperating latch element and cam plate for retracting the former upon movement of the latter, and means for normally retaining said cooperating latch element in engagement with said stationary latch element.

7. In a window control mechanism, a pivotal control arm, a copivotal cam plate having a cam slot and lugs engaging the opposite sides of said control arm, a stationary latch element, a cooperating latch element slidably longitudinally upon said arm, means upon said cooperating latch element and engageable in the cam slot of said cam plate whereby said cooperating latch element is retracted upon movement of said cam plate, and a spring acting on said cooperating latch element for maintaining the same normally in engagement with said stationary latch element.

In testimony whereof I affix my signature.
STANLEY W. NICHOLSON.
